UNITED STATES PATENT OFFICE

ERNEST SCOTT, OF PHILADELPHIA, PENNSYLVANIA

DESIGN FOR GARDEN CHAIR

Application filed June 27, 1929. Serial No. 31,850. Term of patent 7 years.

To all whom it may concern:

Be it known that I, ERNEST SCOTT, a citizen of the United States, residing at 1917 Panama Street, Philadelphia, in the county of Philadelphia and State of Pennsylvania, have invented a new, original, and ornamental Design for Garden Chair, of which the following is a specification, reference being had to the accompanying drawing, forming part thereof.

Figures 1, 2 and 3 are perspective views of my garden chair and Figure 4 is a rear elevation of the same.

I claim:

The ornamental design for garden chair, as shown.

ERNEST SCOTT.
